SHIRT

John Errol Hay, Fulham, London, England

Application December 22, 1932, Serial No. 648,482,
and in Great Britain November 29, 1932

1 Claim. (Cl. 2—118)

This invention refers to improvements in and relating to shirts, more particularly stiff-fronted shirts, the object being to provide a shirt in which the front studs can be placed in position or re-5 placed if necessary, without the necessity of disturbing other articles of clothing in wear at the time.

According to this invention, I provide at each side of the bosom of the shirt, a slit or aperture, large enough for the insertion of the hand, so that, in case of necessity, a stud can be placed 10 in the bosom, whilst the shirt is on the wearer's body without having to disturb other articles of clothing also being worn, and without creasing or 15 crushing the shirt.

The accompanying drawing shows the upper part of a shirt with my invention applied thereto.

As will be seen, the shirt 1 has a vertical slit 2, at each side of the bosom 3 at about the level 20 of the central button hole 4. The slit is so formed that its edges lie close and flat together without any aperture being visible.

It will be obvious that, when the shirt is first put on, it is easier to pass the hand through one of the slits 2 to grasp the base of the stud and hold same, whilst the stud is passed through the stud hole 4 in the upper half of the front, or to 60 hold the base while the upper part of the stud is pushed or screwed home into position, instead of having to pass the hand up from the bottom of the shirt, with its risk of creasing the shirt, and with the awkwardness incident thereto. 65

Similarly should the stud become displaced, it is easier to replace same in position again, or to insert a new stud without having practically to 70 undress first.

I claim:—

A shirt, a slit at each side of the bosom of the shirt at the level of the stud hole and spaced away from the edges of the bosom of the shirt, the edges of the slit lying close and flat together. 75

JOHN ERROL HAY.
